[57] CLAIM

The ornamental design for a bed frame, as shown and described.

DESCRIPTION

FIG. 1 is a front perspective view of a bed frame showing our new design;

FIG. 2 is a side elevational view thereof, both sides being similar;

FIG. 3 is a top plan view thereof;

FIG. 4 is a rear elevational view thereof;

FIG. 5 is an enlarged sectional view taken on line 5—5 of FIG. 2; and FIG. 6 is an enlarged sectional view taken on line 6—6 of FIG. 4.

The rear of the footboard is flat and unornamented.
